H. N. LESSARD

THREAD GUIDE

Filed July 5, 1923

UNITED STATES PATENT OFFICE.

HENRY N. LESSARD, OF MANCHESTER, NEW HAMPSHIRE.

THREAD GUIDE.

Application filed July 5, 1923. Serial No. 649,558.

To all whom it may concern:

Be it known that I, HENRY N. LESSARD, a citizen of the United States, residing at Manchester, in the county of Hillsborough and State of New Hampshire, have invented certain new and useful Improvements in Thread Guides, of which the following is a specification, reference being had to the accompanying drawings.

10 This invention relates to certain improvements in thread guides and has relation more particularly to a device of this general character especially designed and adapted for use in spooling and it is an object of the invention to provide a device of this general character having novel and improved means whereby scraping of the yarn is prevented as the same travels through the guide.

Another object of the invention is to provide a novel and improved device of this general character comprising an adjuster wheel to effect the proper setting of the thread on the spools.

It is also an object of the invention to provide a novel and improved guide of this general character which operates to prevent the making of bad spools and which comprises in its construction a tension post which operates, as the spool grows larger, to increase the tension on the thread and thus make a harder and better spool.

The invention consists in the details of construction and in the combination and arrangement of the several parts of my improved thread guide whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view somewhat of a diagrammatic character partly in elevation and partly in section illustrating a thread guide constructed in accordance with an embodiment of my invention;

Figure 2 is a view partly in section and

partly in top plan of the guide as illustrated in Figure 1;

Figure 3 is a view in front elevation of my improved guide as herein set forth;

Figure 4 is a sectional view taken substantially on the line 4—4 of Figure 2;

As disclosed in the accompanying drawings, B denotes an arm or rod suitably supported by the spooler and with which is clamped or otherwise secured a tensioning device.

The tensioning device as herein disclosed comprises two sections X and Y. The section X comprises a base block 1 provided at its forward marginal portion with an upstanding blade 2, the block 1 having its lower portion extending beyond the inner edge of the blade. The section Y includes a base 3 having an upper extension 4 overlying the extended portion 5 of the base 1 of the section X and the forward portion of the base 3 and the extension 4 thereof is provided with an upstanding blade 6 substantially in duplicate of the blade 2. The opposed edges of the blades 2 and 6 have their lower portions in parallelism with their upper portions disposed on predetermined outward curvatures.

The sections X and Y are adapted to be adjusted one with respect to the other in accordance with the count or number of yarn desired and as herein disclosed this adjustment is effected through the instrumentality of the bolt 7 disposed loosely through the outer end of the base 3 of the section Y and in threaded engagement with the opposed end portion of the extension 5 of the base 1 of the section X, as is particularly illustrated in Figure 4. The head

7a of the bolt 7 has direct contact with the outer end of the base 3 so that when the bolt 7 is turned in one direction the section Y will be moved toward the section X. The opposed faces of the base 3 and the extension 5 are provided with the registering or aligned sockets 8 in which is mounted an expansible member 10 herein disclosed as a coiled spring encircling the bolt 7. When the bolt 7 is rotated in the reversed direction, the spring or expansible member 10 serves to move the section Y in a direction away from the section X.

The thread from the bobbin Z or the like is dropped by the spool tender between the jaws afforded by the blades 2 and 6 and thence to the spool S it being understood 5 that the sections X and Y having been first relatively adjusted in accordance with the count or number of the thread or yarn.

In order to assure the maintenance of 10 the sections X and Y in desired adjusted relation I find it of advantage to employ the holding screw 11 threaded through the base 3 and having clamping contact with the bolt 7.

Extending upwardly from the base 3 inwardly of but in close proximity to the blade 6 is a tension post 12 which serves to prevent the thread from scraping on the right blade 6 and as the spool grows bigger, the post 12 will give an added tension to the 20 thread resulting in a harder and better spool.

Extending outwardly from the base 1 adjacent the outer end thereof is an arm 15 and extending inwardly from the arm 15 25 and carried thereby is a stub shaft 16, said shaft having its outer or free end terminating in close proximity to the free end of the extension 5 of the base 1.

Eccentrically mounted upon the stub 30 shaft 16 is an adjustable wheel 17 the periphery of which being grooved to receive a thread.

Threaded upon the stub shaft 16 at opposite sides of the wheel 17 are the clamping 35 nuts 18 which serve to hold the adjuster wheel in its different positions about the shaft 16. By proper rotation of the wheel 17, a proper setting will be effected of the thread with respect to the spools, the wheel 40 being adjustable to vary the path of the thread through the guide to minimize wear.

From the foregoing description it is thought to be obvious that a thread guide constructed in accordance with my invention 45 is particularly well adapted for use by reason of the convenience and facility with which it may be assembled and operated, and it will also be obvious that my invention is susceptible of some change and modification 50 without departing from the principles and spirit thereof and for this reason I do not wish to be understood as limiting myself to the precise arrangement and formation of the several parts herein shown in carrying 55 out my invention in practice except as hereinafter claimed.

I claim:—

1. A guide of the class described comprising two sections, means for adjusting the 60 same one with respect to the other, said sections being provided with upstanding blades providing jaws between which a thread is adapted to be disposed, and an upstanding guiding post carried by one of the sections, 65 a side of the guide post being substantially

aligned with the inner edge of one of the blades.

2. A guide of the class described comprising two sections, means for adjusting the same one with respect to the other, said sections being provided with upstanding blades 70 providing jaws between which a thread is adapted to be disposed, and an upstanding guiding post carried by one of the sections rearwardly of the blade carried by said section, a side of the post being substantially aligned with the inner edge of said blade.

3. A guide of the class described comprising two sections, means for adjusting the same one with respect to the other, said sections being provided with upstanding blades 80 providing jaws between which a thread is adapted to be disposed, an upstanding guiding post carried by one of the sections, and vertically adjustable means carried by one 85 of the sections for setting the thread, said vertically adjustable means and a side of the post being substantially aligned with the jaw between the blades.

4. A guide of the class described comprising two sections, means for adjusting the same one with respect to the other, said sections being provided with upstanding blades 90 providing jaws between which a thread is adapted to be disposed, an upstanding guiding post carried by one of the sections, and an eccentrically mounted wheel carried by one of the sections, said wheel 95 and a side of the post being substantially aligned with the jaw between the blades.

5. A guide of the class described comprising two sections, means for adjusting the same one with respect to the other, said sections being provided with upstanding blades 100 providing jaws between which a thread is adapted to be disposed, an upstanding guiding post carried by one of the sections, and an eccentrically mounted wheel carried by one of the sections, in advance 105 of the blade carried thereby, said wheel and a side of the post being substantially aligned with the jaw between the blades.

6. A guide of the class described comprising two sections, means for adjusting the same one with respect to the other, said sections being provided with upstanding blades 110 providing jaws between which a thread is adapted to be disposed, an upstanding guiding post carried by one of the sections, an outstanding arm carried by one of the sections, a stub shaft carried by said arm, an adjuster wheel eccentrically mounted on said 115 stub shaft, and means for holding said wheel against movement about the stub shaft, said wheel and a side of the post being substantially aligned with the jaw between the blades.

7. A guide of the class described comprising a member provided with a slot through 120 which a thread is adapted to be disposed, an 125

upstanding guide post carried by the member and having a side thereof substantially aligned with an edge of the slot, and means carried by said member to vary the path 5 of the thread through the slot.

8. A guide of the class described comprising a member provided with a slot through which a thread is adapted to be disposed, an upstanding guide post carried by the

member and having a side thereof substantially aligned with an edge of the slot, and means carried by said member to vary the path of the thread through the slot, said post being rearwardly of the slot.

In testimony whereof I hereunto affix my 20 signature.

HENRY N. LESSARD.
